Primary Examiner — Cynthia Ramirez*Assistant Examiner* — Michael A Maharajh(74) *Attorney, Agent, or Firm* — Dunlap Bennett & Ludwig PLLC(57) **CLAIM**

The ornamental design for a handle for exercise equipment, as shown and described.

DESCRIPTION

FIG. 1 is a front perspective view of a handle for exercise equipment, showing my new design;

FIG. 2 is a front elevation view thereof;

FIG. 3 is a rear elevation view thereof;

FIG. 4 is a left elevation view thereof, the right elevation view being a mirror image thereof;

FIG. 5 is a top plan view thereof;

FIG. 6 is a bottom plan view thereof; and,

FIG. 7 is a front perspective view of the handle for exercise equipment shown in use.

The evenly-sized broken lines showing exercise equipment in FIG. 7 depicts environmental subject matter that forms no part of the claimed design, while the remaining evenly-sized broken lines shown in the drawings depict portions of the handle for exercise equipment that form no part of the claimed design.

The dash-dot broken lines in the drawings depict the boundary of the claimed invention and it is understood that the claim extends to the boundary, which form no part of the claimed design.
